Primary Examiner — Ania Aman(74) *Attorney, Agent, or Firm* — Middleton Reutlinger(57) **CLAIM**

The ornamental design for a manifold, as shown and described.

DESCRIPTION

FIG. 1 is an upper perspective view of a manifold showing our new design;

FIG. 2 is a lower perspective view of the design of FIG. 1;

FIG. 3 is a top view of the design of FIG. 1;

FIG. 4 is a bottom view of the design of FIG. 1;

FIG. 5 is a first side view of the design of FIG. 1;

FIG. 6 is a second side view of the design of FIG. 1;

FIG. 7 is a front view of the design of FIG. 1; and,

FIG. 8 is a rear view of the design of FIG. 1.

In the drawings, the broken lines depict unclaimed portions of the manifold only and form no part of the claimed design.
